UNITED STATES PATENT OFFICE

JOHN P. COLEMAN, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed December 6, 1929. Serial No. 412,078.

My invention relates to railway traffic controlling apparatus, and more particularly to apparatus for operating railway switches and is an improvement over the apparatus disclosed in United States Patent No. 1,238,889 granted to me on September 4, 1917, for railway traffic controlling apparatus.

I will describe one form of apparatus embodying my invention, and will then point out the novel features thereof in claims.

In the accompanying drawings, Fig. 1 is a top plan view showing one form of apparatus embodying my invention with the covers of the transmission and control housings removed. Fig. 2 is a longitudinal sectional view taken on line II—II of Fig. 1. Fig. 3 is a horizontal sectional view taken on line III—III of Fig. 2. Fig. 4 is a longitudinal sectional view of a portion of the structure shown in Fig. 2, illustrating the positions that certain parts assume when the apparatus is operated manually. Fig. 5 is an enlarged detail elevational view illustrating the latch mechanism shown in the preceding views. Fig. 6 is a view of the right-hand end of the structure shown in Fig. 1 with the retaining plate 83 removed. Fig. 7 is a fragmentary vertical sectional view taken on line VII—VII of Fig. 3.

Similar reference characters refer to similar parts in each of the several views.

Referring to the drawings, an apparatus constructed in accordance with my invention is shown as comprising a transmission housing 1, provided with a cover 2. A cylinder housing 3 is secured to one side of the housing 1 by bolts 4 and a control and guide housing 5, provided with a cover 6 is formed integrally with the other side thereof. These housings are secured to the ties 7 of a railway track by means of bolts 8 and 9 extending through feet on the housings 3 and 5, as shown in Fig. 1.

The cylinder housing 3 is formed with two parallel cylinders 10^a—10^b which are closed at their outer ends by cylinder heads 11^a—11^b and which communicate at their inner ends with the transmission housing 1 through openings 12^a—12^b (Fig. 3). Pistons 13^a—13^b are mounted for reciprocation within the cyl-

inders 10^a—10^b and are carried by the ends of a pair of rack bars 14^a—14^b which extend inwardly through the openings 12^a—12^b for intermeshing engagement with the opposite sides of a gear wheel 15. This gear wheel is fixed to the upper end of a vertically extending stud shaft 16 which is journaled at its lower end in a bearing 17 provided in the housing 1. Secured in the housing 1 is a plate 19, provided with a bearing 18 in which is journaled the upper end of the stud shaft 16. A crank 20 is fixed to the lower end of the shaft 16 and carries a roller 21 for engagement with a slot 22 formed in a member 23 carried by a switch operating rod 24 (Fig. 2). This rod is slidably mounted in the housing 1 and is adapted to be connected at its outer end with the movable rails of a track switch or other governing device not shown in the drawing.

Fluid pressure is admitted to the interior of the cylinders 10^a—10^b through ports 25^a—25^b which are provided in the cylinder heads 11^a—11^b and which communicate with pipes 26^a—26^b through valves 27^a—27^b, as best seen in Fig. 3. When the valves occupy the position shown in Fig. 2, communication is established between the pipes 26^a—26^b and the interiors of the cylinders, but when they are moved to the position shown in Fig. 4, communication with the source of air under pressure is interrupted and communication is established between the interiors of the cylinders and the outer atmosphere, through vent ports 28^a—28^b. During the normal operation of the device these valves occupy the open position illustrated in Fig. 2 and the supply of fluid pressure is alternately admitted to the cylinders 10^a—10^b through suitable valves (not shown) provided in the pipes 26^a—26^b. It will be noted that when one of the pistons 13^a—13^b is at the limit of its travel in one direction, the other piston occupies a position at the limit of its travel in the opposite direction. It should also be pointed out that when fluid pressure is admitted to the cylinder 10^a, for example, through pipe 26^a so as to force the rack bar 14^a to the right, as viewed in Fig. 2, in order to rotate the gear wheel 15 and parts

55

100

driven thereby in a clockwise direction, the rack bar 14^b and piston 13^b will be moved to the left. When fluid pressure is admitted to the cylinder 10^b through pipe 26^b the parts will move in opposite directions.

Fluid pressure may be supplied to pipes 26^a and 26^b selectively for the control of the apparatus by any suitable means not shown in the drawing.

10 The pistons 13^a—13^b are formed with centrally disposed outwardly extending plungers 29^a—29^b adapted to enter axially disposed cylindrical bores 30^a—30^b provided in the cylinder heads 11^a—11^b, as the pistons 15 approach the limits of their strokes. The bores 30^a—30^b communicate directly with the inlet passages 25^a—25^b and, therefore, the plungers 29^a—29^b greatly restrict communication between these passages and the 20 interiors of the cylinders shortly before the movements of the pistons terminate. A quantity of fluid is, therefore, trapped in the ends of the cylinders, and this trapped fluid cushions the action of the entire apparatus.

25 The right-hand ends of the rack bars 14^a—14^b as viewed in the drawings, that is to say, the ends opposite to the pistons 13^a—13^b, are provided with heads 31^a—31^b which are slidably mounted in cylindrical guideways 32^a—32^b formed in the housing 5 and are formed with locking dogs 33^a—33^b on their outer faces. These dogs are offset slightly relative to one another in a vertical direction and are adapted to project through 30 openings 34^a—34^b in a guide plate 35. This plate is formed with a pair of horizontal guideways 77 and 78 (Figs. 2, 6 and 7) which are arranged one above the other in spaced parallel relation and which intersect 35 the openings 34^a—34^b. A locking slide 79 is mounted in the guideway 77 and is provided with a notch or recess 80 in its lower edge adapted to register with the opening 34^a at certain times for engagement by the dog 33^a. Similarly, a locking slide 81 is mounted in the guideway 78 and is provided with a notch or recess 82 in its upper edge adapted to register with the opening 34^b at certain other times for engagement by the dog 33^b. The slides 79 and 81 are maintained against displacement from their respective guideways by a retaining plate 83 which is secured to the outer face of the guide plate 35.

40 An arm 84 is fixed to one end of the lower slide 81 for adjustable connection with the adjacent end of the upper slide 79 and not only insures that the slides move in unison but permits them to be adjusted longitudinally relative to each other according to the degree of movement of the track switch. The other end of the lower slide 81 is adapted to be adjustably connected with one end of a switch lock rod not shown. By means 45 of the above described construction if either

of the plungers 33^a or 33^b is in engagement with its cooperating notch 80 or 82 the switch will be maintained positively against displacement in the position to which it was last moved even though the switch operating rod 24 may thereafter be disconnected or broken.

45 The apparatus is provided with an indication circuit controller for establishing different circuits when the apparatus occupies different positions. For example, the controller may be employed to operate a signal for indicating the condition of the trackway switch operated by the apparatus. This indication controller is contained within the housing 5 and comprises a central block 38 of insulating material and blocks 39^a—39^b, also of insulating material, arranged in spaced parallel relation thereto on opposite sides thereof (Figs. 1 and 2). The central 50 block 38 carries a set of spring contact fingers 40^a for engagement with contact tips 41^a—42^a mounted on the block 39^a and a set of contact fingers 40^b for engagement with contact tips 41^b—42^b mounted on the block 39^b. The 55 fingers 40^a—40^b are shifted into and out of engagement with their associated contact tips, by means of blocks 43^a—43^b of insulating material which are mounted for longitudinal sliding movement between the central block 38 and the outer blocks 39^a—39^b. The blocks 43^a—43^b are provided with pairs of vertically extending pins 44^a—44^b for engagement with the opposite sides of each of the contact fingers 40^a and 40^b respectively, and are shifted longitudinally by means of a pair of bell crank levers 45^a—45^b. These levers are pivotally mounted on the plate 19, as at 46^a—46^b, and the arms 47^a—47^b thereof are connected with the blocks 43^a—43^b by links 48^a—48^b. The other arms 49^a—49^b of the levers 45^a—45^b are provided with rollers 50^a—50^b for engagement with a cam 51 which is fixed to the upper end of the stud shaft 16 and which is provided with a reentrant portion or notch 52. The arms 49^a—49^b of the levers are connected by means of a coiled spring 53 so as to normally bias the arms 49^a—49^b of these levers towards each other, and the rollers 50^a—50^b carried thereby into engagement with the cam 51.

55 The parts are so constructed and proportioned that when the piston 13^b reaches the limit of its travel toward its right-hand position shown in Fig. 3, the cam 51 has been rotated to its extreme counter-clockwise position in which the notch 52 therein registers with the roller 50^a of the bell crank lever 45^a. This permits the lever 45^a to swing in a counter-clockwise direction and cause the engagement of the fingers 40^a with their associated contact tips 42^a. During these movements of the parts the high portion of the cam 51 maintains the bell crank lever 45^b in a position in which the fingers 40^b are in en-

gagement with their co-operating contact tips 41^b. When the piston 13^a moves to the right, however, the cam 51 is rotated in a clockwise direction. At the beginning of 5 this movement the roller 50^a is first forced outwardly from engagement with the notch 52 which causes the bell crank lever 45^a to swing about its pivot in a clockwise direction. This causes the contact fingers 40^a to move out 10 of engagement with the contact tips 42^a and into engagement with the tips 41^a. When the piston 13^a reaches the limit of its movement to the right the cam 51 has been rotated to a 15 position in which the notch 52 registers with the roller 50^b of the bell crank lever 45^b. This permits the bell crank 45^b to swing about its pivot in a clockwise direction and cause the contact fingers 40^b to move out of engagement with the contact tips 41^b and into engagement with their associated contact tips 20 42^b. It will be noted that, by reason of the fact that there is but a single notch 52 in the cam 51, the levers 45^a—45^b operate in succession and that when one of these levers 25 occupies its innermost position the other lever is in its outermost position. As a result, certain of the contacts controlled by one of the levers 45^a—45^b are opened and others closed at the beginning of the movement of 30 the mechanism in either direction but the contacts controlled by the other of these levers are not disturbed until the movements of the parts terminate.

It occasionally is necessary to operate the 35 switch manually and independently of the fluid pressure mechanism. At such times it is desirable to interrupt the supply of fluid pressure to the cylinders 10^a—10^b of the apparatus so as to prevent it from being operated 40 thereby while it is being operated manually and to eliminate the possibility of injury to the operator as a consequence. According to my invention it is impossible to actuate the switch manually as long as the cylinders are 45 in communication with the source of fluid pressure, and conversely, it is impossible to operate the switch by fluid pressure while it is in condition to be operated manually. Also, it is desirable to render the circuit 50 controller ineffective during the manual operation of the switch so as not to cause the display of false signals. I accomplish this by the following described construction.

- A gear wheel 54 (Fig. 2) is secured to the 55 upper face of the gear wheel 15 and as shown in Fig. 4, this gear wheel 54 is adapted to be rotated manually by means of a pinion 55 fixed to the lower end of a shaft 56 which is provided at its upper end with a crank handle 57. This pinion is adapted to be inserted 60 into the housing 1 through an aperture 58 provided in the cover 2, through a bearing 59 formed on the plate 19 and into intermeshing engagement with the gear wheel 54. The 65 lower end of the pinion 55 is provided with an

axially arranged gudgeon 60 for rotatable engagement with a step bearing or seat 61 formed in the housing 1 so as to maintain the pinion in intermeshing engagement with gear wheel 54 during the manual operation of the device.

During the operation of the device by fluid pressure, access to the gear 54 through the bearing 59 is prevented by means of a rod 62 which is slidably mounted in a bearing 63 70 carried by the housing 1 and which projects through diametrically disposed apertures 64 provided in the bearing 59. This rod forms an obstruction across the opening in the bearing 59 and prevents the pinion 55 from being inserted as long as the rod 62 occupies this position. The outer end of the rod 62 is pivotally connected, by means of a link 65, with a T-shaped member 66 which is formed with sockets at each end for engagement with the squared confronting ends 67^a—67^b of the valves 27^a—27^b and which is provided with a socket 68 adapted to receive a removable operating lever such as the operating arm of the pinion 55.

When the valves 27^a—27^b occupy the positions shown in Fig. 2, in which communication is established between the pressure supply pipes 26^a—26^b and the interior of the cylinders, the rod 62 completely obstructs the opening in the bearing 59, thereby rendering it impossible for the pinion 55 to be inserted in order to operate the switch manually. However, if it is desired to operate the switch by means of the pinion 55, a lever is inserted 100 in the socket 68 and the member 66 and the valves 27^a—27^b are turned to the positions shown in Fig. 4 of the drawings, in which communication between the supply fluid pressure and the interiors of the cylinders 105 10^a—10^b is interrupted and in which communication is established between the cylinders and the outer atmosphere through the vent ports 28^a—28^b. When the member 66 is thus operated, the rod 62 is withdrawn 110 longitudinally through the apertures 64 in the bearing 59 to the retracted position illustrated in Fig. 4, in which it no longer prevents access through the opening in this bearing. This permits the pinion 55 to be inserted 115 in the bearing 59 in order to manually rotate the gear 54 and parts driven thereby.

It is also desirable to render ineffective the indication circuits when the switch is operated manually. This is accomplished by 120 means of a latch mechanism comprising a pair of levers 69^a—69^b (Figs. 1 and 5) which are mounted on studs 70^a—70^b carried by the plate 19. These levers are provided with arms 71^a—71^b, which extend inwardly towards each other and which are provided with rounded extremities 72^a and 72^b for engagement with the inner end of the rod 62. The levers 69^a—69^b are also provided with arms 73^a—73^b formed with notched extremi- 130

ties 74^a—74^b for engagement with the ends of the arms 49^a—49^b of the bell crank levers 45^a—45^b. The levers 69^a—69^b are biased about their pivots in opposite directions, so that the arms 71^a—71^b thereof bear against the end of the rod 62, by means of a coil spring 75 which connects arms 76^a—76^b formed on these levers. When the rod 62 occupies the position shown in Fig. 2, in which 10 the several instrumentalities occupy positions permitting of the operation of the device by fluid pressure, the rod 62 maintains the levers 69^a—69^b in the positions illustrated in Figs. 1 and 5 of the drawings and in which the 15 arms 73^a—73^b are held out of the path of movement of the arms 49^a—49^b of the bell crank levers 45^a—45^b. However, when it is desired to operate the device manually, the 20 valves 27^a—27^b are first operated to disconnect the device from the source of fluid pressure as hereinbefore described, and the rod 62 is simultaneously withdrawn from engagement with the arms 71^a—71^b. This permits the levers 69^a—69^b to swing about their pivots 25 under the action of the spring 75 until their movement is arrested by the ends of the arms 49^a—49^b of the levers 45^a—45^b. Now, if when levers 69^a—69^b are thus released, the cam 51 occupies the position shown in Fig. 1, 30 in which the lever 45^a is at the limit of its inward movement and the lever 45^b occupies its outermost position, the portion of the arm 69^a between the pivot 71^a and its notched extremity 74^a will contact with the arm 49^a, 35 while the notched extremity 74^b of the arm 69^b will engage the end of the arm 49^b and prevent it from moving inwardly when released by the cam 51. If the apparatus is now operated manually, rotation of cam 51 40 will force the lever 45^a about its pivot in a clockwise direction until its end registers with the notch 74^a in the arm 69^a and is engaged thereby. The bell crank levers 45^a and 45^b will therefore both be held in their outermost 45 positions with the circuit controller properly conditioned as long as the apparatus is operated manually. The operation of the apparatus when actuated manually while roller 50^b occupies the notch 52 in cam 51, will be 50 readily understood from the foregoing description.

When the pinion 55 is removed and the T-shaped member 66 is restored to the position shown in Fig. 2 in order to condition the apparatus for subsequent operation by fluid pressure, the rod 62 is again projected across the opening in the bearing 59 and into engagement with the rounded extremities of the arms 71^a—71^b. This swings the levers 69^a—69^b back to their normal ineffective positions out of engagement with the bell crank levers 45^a—45^b and releases the levers, so as to permit of the operation of the circuit controller 65 as previously described.

From the foregoing it will be apparent that I have provided a very simple and efficient construction which renders it imperative that the operator shall first disconnect the device from the source of fluid pressure before it is possible to operate the switch manually, and by means of which the possibility of injury to the operator and danger to traffic over the trackway through the display of false signals is to a large extent 70 eliminated. 75

Although I have herein shown and described only one form of railway traffic-controlling apparatus embodying my invention, it is understood that various changes and modifications may be made therein within the scope of the appended claims without departing from the spirit and scope of my invention. 80

Having thus described my invention, what I claim is: 85

1. In combination, transmission mechanism for operating a railway traffic controlling device, fluid pressure means for operating said mechanism, manual means for operating said mechanism, governing means for selectively rendering said fluid pressure means effective and ineffective, and means actuated by said governing means for controlling the operation of said manual operating 90 means. 95

2. In combination, transmission mechanism for operating a railway traffic controlling device, fluid pressure means for operating said transmission mechanism, means for operating said mechanism manually, valve mechanism for controlling the operation of said fluid pressure means, and means controlled by the position of said valve mechanism for controlling the operation of said 105 manual operating means. 110

3. In combination, transmission mechanism for operating a railway traffic controlling device, a fluid pressure device for operating said mechanism, a valve for controlling the admission of fluid pressure to said fluid pressure device, means for operating said mechanism manually, and means associated with said valve for preventing said mechanism from being operated manually when said valve is open and for permitting the operation of said mechanism normally when said valve is closed. 115 125

4. In combination, transmission mechanism for operating a railway traffic controlling device, fluid pressure means for operating said mechanism, a valve for controlling the admission of fluid pressure to said fluid pressure means, means for operating said mechanism manually, means actuated by the operation of said valve to prevent the manual operation of said mechanism when said valve is open and to permit the manual operation of said mechanism when said valve is closed. 120 125 130

5. In combination, transmission mechanism for operating a railway traffic controlling device, fluid pressure means for operating said mechanism, a valve for controlling the admission of fluid pressure to said fluid pressure means, an indicating device associated with said mechanism, means for manually operating said mechanism, and means actuated by the operation of said valve to render said indicating device ineffective when said mechanism is operated manually.

6. Railway traffic controlling device comprising a gear, fluid pressure means for operating said gear, a valve for controlling the admission of fluid pressure to said fluid pressure means, a bearing adapted to maintain a removable manually operated pinion in operative position with respect to said gear and a rod operatively connected with said valve and extending through said bearing for obstructing access to said bearing when said valve is open and for permitting said pinion to be mounted in said bearing for the manual operation of said gear when said valve is closed.

7. Railway traffic controlling apparatus comprising a housing, a gear mounted in said housing, fluid pressure means for operating said gear, a valve for controlling the admission of fluid pressure to said fluid pressure means, an indicating device operated by said gear, a seat in said housing adapted to locate a removable manually operated pinion in operative position relative to said gear, and means actuated by the operation of said valve for preventing access to said seat when said valve is open and for permitting said pinion to be positioned therein for the manual operation of said gear and for disconnecting said indicating device from said gear when said valve is closed.

8. Railway traffic controlling apparatus comprising a housing, a gear in said housing, fluid pressure means for operating said gear, a valve for controlling the admission of fluid pressure to said fluid pressure means, a cam operated by said gear, lever mechanism operated by said cam, an indicating device operated by said lever mechanism, latch mechanism mounted for movement into and out of the path of movement of said lever mechanism, a seat in said housing for locating a removable manually operable pinion in operative position relative to said gear, and means actuated by the operation of said valve for obstructing access to said seat and for maintaining said latch mechanism out of the path of movement of said lever mechanism to permit of the operation of said indicating device by said lever mechanism when said valve is open, and for permitting said pinion to be positioned in said seat for the manual operation of said gear and for permitting said latch mechanism to move into the path of movement

of said lever mechanism to modify operation of said indicating device when said valve is closed.

In testimony whereof I affix my signature.
